BRANDING DEVICE FOR BARBECUED STEAKS

Klarence F. Krone, Jr., Van Nuys, Calif., assignor to Lon-krone Company, Los Angeles, Calif., a partnership

Application January 10, 1955, Serial No. 33,905

Term of patent 14 years

(Cl. D11—1)

Fig. 1

Fig. 2

Fig. 3

Fig. 4

Fig. 5

Figure 1 is a side view of a branding device for barbecued steaks, showing my new design;

Fig. 2 is an enlarged end view thereof;

Figs. 3, 4, and 5 are elevational views of the indicia comprising the three sides of the branding device; and

Fig. 6 is a perspective view of the branding head end of the device with the handle shown fragmentarily.

I claim:

The ornamental design for a branding device for barbecued steaks, as shown.
